UNITED STATES PATENT OFFICE

98,406

DESIGN FOR A CONTAINER FOR FLOWERS

Pauline Wilcox Smith, Waterbury, Conn.

Application March 22, 1935, Serial No. 55,999

Term of patent 7 years

To all whom it may concern:

Be it known that I, Pauline Wilcox Smith, a citizen of the United States, residing at Waterbury, in the county of New Haven and State of Connecticut, have invented a new, original, and ornamental Design for a Container for Flowers, of which the following is a specification, reference being had to the accompanying drawing, forming part thereof.

Fig. 1 is a side view of a container for flowers showing my new design;

Fig. 2 is a front view of the same; and

Fig. 3 is a perspective view thereof.

The design is characterized by two abutting, smooth, vertical, cylindrical containers having their open upper ends rimmed and having circumferential beads below such rimmed edges and one being substantially half the height of the other, so that their open upper ends are in widely-separated planes, and the containers being located on opposite sides of a vertical handle formed at its upper end with a loop.

I claim:

The ornamental design for a container for flowers substantially as shown and described.

PAULINE WILCOX SMITH.
